UNITED STATES PATENT OFFICE.

JAMES MERRYWEATHER, OF GREENCASTLE, INDIANA.

TRAIN CONNECTION.

Application filed January 8, 1926. Serial No. 80,102.

This invention relates to a train connection and is designed primarily as an improvement upon the structure disclosed in Patent 1,121,522 issued to me on December 5, 1914.

In the patented structure a means is provided for simultaneously lifting a coupling pin and breaking the connection between the couplings of the flexible hose. It has been found in practice, however, that because of the constantly changing positions of the connected cars relative to each other, it is practically impossible to effect simultaneous uncoupling of the car couplers and uncoupling of the hose connections. Instead one or the other will remain coupled in many instances with the result that injury to some part is likely to occur or else the coupling operation will not be completed.

The present invention is designed to insure uncoupling of the parts in properly timed relation so that the objections heretofore present will be overcome.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings the preferred form of the invention has been shown.

In said drawings,

Figure 1 is a horizontal section through end portions of two cars the coupling means and the mechanism provided for uncoupling, 40 being shown in plan.

Figure 2 is a section on line 2—2 Figure 1.

Figure 3 is a perspective view of the operating member.

Figure 4 is a transverse section through the shaft of the operating member and a portion of the lost motion connection.

Figure 5 is a section on line 5—5 Figure 4.

Referring to the figures by characters of reference A designates end portions of cars connected in the usual way by means of couplings B of the "Janney" type wherein pins C are employed for preventing uncoupling. Portions of pipe lines have been shown at D and these are provided with

flexible hose E having coupling members F of the usual type one of which is adapted to

be lifted relative to the other for the purpose of uncoupling the hose.

For the purpose of actuating the pins C and the couplings F so as to completely disconnect the cars A whenever desired, each car is provided at each end with a transverse shaft 1 mounted for rotation in suitable bearings 2 and provided at one or both ends with a crank arm 3 or the like whereby the shaft 65 can be rotated readily. Secured to the shaft so as to move therewith is a radial arm 4 provided with a chain 5 or other suitable flexible connection whereby the arm is connected to one of the members F of the hose 70 coupling thereunder.

Another arm 6 is mounted loosely on the shaft 1 between collars 7 which serve to hold arm 6 against lateral displacement. This arm 6 is connected by a chain 8 or the like 75 to the pin C thereunder. A cross strip 8 connects the collars 7 and is so positioned that after the shaft 1 has been rotated a predetermined distance in one direction said strip will come against the arm 6 and swing it upwardly so as to pull through the connection 8 upon the pin C.

When it is desired to uncouple the cars A the shaft 1 is rotated in the direction indicated by the arrow in Figure 4. Thus the arm 4 will promptly pull through the chain or other connection 5 upon one of the coupling members F so as to uncouple the hose. During this operation the strip 8 is travelling forwardly toward the arm 6 and immediately following the uncoupling of the hose, strip 8 comes against the arm 6 and swings it upwardly. Said arm will thus pull through the connection 8 upon the pin C and raise it so as to release the coupling B and complete the uncoupling operation. Obviously by providing the lost motion connection formed by the strip 8 and the arm 6 the coupling member F and the pin C will be operated in properly timed succession and there will be no danger of either premature or delayed operation of either of the parts and consequent failure of the uncoupling operation.

It is to be understood that any desired 105 number of hose connections may be provided and in that event additional arms 4 can be used for operating the connections between the hose.

What is claimed is:

1. The combination with railway cars, 110 couplings carried thereby and adapted to

interlock, pins for holding the couplings against separation, pipe lines including a flexible hose, and couplings between the hose, of a rotatable shaft upon each car, and means 5 operated by the rotation of the shaft in one direction for first disconnecting the hose coupling and thereafter lifting a pin to release the car couplings.

2. The combination with railway cars, 10 couplings carried thereby adapted to interlock, pipe lines, and couplings for connecting the pipe lines, of means upon one of the cars rotatable in one direction for first disconnecting the coupling of the pipe lines and 15 thereafter disconnecting the car couplings.

3. The combination with railway cars,

normally interlocked couplings carried thereby, pipe lines, and normally interlocked couplings connecting the pipe lines, of a shaft on one of the cars, means for rotating the same, a lifting arm movable with the shaft, a connection between said arm and one of the couplings of the pipe line, a lifting arm connected to one of the car couplings, and a lost motion means operated by the 20 shaft for actuating the lifting arm of the car coupling subsequently to the actuation of the pipe line coupling by the other arm.

In testimony that I claim the foregoing as my own, I have hereto affixed my signature. 25

JAMES MERRYWEATHER.
